his Attorney.

UNITED STATES PATENT OFFICE.

THOMAS S. PLIKERD, OF DELPHOS, OHIO.

WINDOW SHADE AND CURTAIN HOLDER DEVICE.

No. 909,452.

Specification of Letters Patent.

Patented Jan. 12, 1909.

Application filed April 7, 1908. Serial No. 425,664.

To all whom it may concern:

Be it known that I, THOMAS S. PLIKERD, a citizen of the United States, residing at Delphos, in the county of Allen and State of Ohio, have invented certain new and useful Improvements in Window Shade and Curtain Holder Devices, of which the following is a specification, reference being had thereto to the accompanying drawing.

10 This invention relates to an improvement in a window shade and curtain-holder, and has for its object the provision of means for facilitating the supporting of a curtain-pole and a window-shade upon a window frame.

15 Another object of this invention is the construction of a device which can be adjusted to different positions upon a window frame for accommodating shades or poles of different lengths, and said device comprises

20 a minimum number of parts, is simple in operation, and comparatively inexpensive to construct or manufacture.

25 With these and other objects in view, this invention consists of certain novel constructions, combinations, and arrangements of parts, as will be hereinafter fully described and claimed.

30 In the drawings: Figure 1 is a perspective view of a device constructed in accordance with the present invention, showing the same as it appears when attached to a window frame. Fig. 2 is a top plan view of the clamp device. Fig. 3 is a view in side elevation of the bracket. Fig. 4 is a perspective view of the sliding jaw of the clamp.

35 Referring to the drawings, by numerals, 1 designates a straight bar or strip of metal, constituting the body of the clamp, which body or bar 1 is provided at one end with a 40 right-angled portion 2, terminating in a penetrating point 3, formed at an angle to the extension 2; the extension 2 and the penetrating point 3 constitute a stationary or fixed jaw. At the opposite end of the 45 straight body 1 and, preferably, positioned at right-angles and integral therewith, is an apertured extension 4. Threaded into the aperture of extension 4 is a thumb-screw or bolt 5, which bolt normally engages, at its 50 inner end, the sliding jaw carried by and slidably mounted upon the body or straight bar-portion 1 of the clamp.

The sliding jaw comprises an angle-body portion, including portions 6 and 7. Integral with the outer portion 6 is a sharpened 55 or penetrating point 8, which is adapted to be forced into the frame 9. The portion 7 is, preferably, formed at right-angles to portions 6, and the outer end of said portion terminates in an angularly-disposed lug 10, 60 The lug 10 is provided with an elongated aperture 11. Integral with the inner ends of portions 7 and 8, and parallel with lug 10, is an auxiliary lug 12, which is also provided with an elongated aperture 11. The apertures 11 register, and prior to the bending of the apertured extension 4 at an angle to the body portion 1, said sliding jaw, through the medium of apertures 11, is slid upon the body, and said jaw may, normally, slide 70 longitudinally of the straight, flat body 1.

When it is desired to secure the clamp to the window frame 9, all that is necessary is to thread the bolt or screw outward and adjust the clamp upon the frame so that the 75 fixed jaw engages one side of the frame, and the sliding jaw is positioned contiguous to the other side, and, then, by rotating the bolt 5, for causing said bolt to move inward, said bolt will eventually engage the outer 80 face of portion 6 and the sliding jaw will force the penetrating point of portion 8 of said jaw into the frame, and at the same time will force the point or portion 3 into the frame, thereby fixedly securing the 85 clamp in an adjusted position upon said frame.

The bracket of the device is formed from a single piece or strip of resilient metal and comprises a vertical body portion 13, terminating at its upper end in an angularly-disposed portion 14, having a curtain-pole receiving socket formed at its outer end. The vertical portion 13 terminates at its lower end in an integral, parallel portion 16, which is provided with an outwardly bulged portion 17, conformed to the shape of the body 1, so that said body is normally positioned between the vertical portion 13 and the outwardly bulged portion 17. The parallel or auxiliary portion 16 terminates at its upper end in an outwardly-extending, right-angle portion 18; the outer end of portion 18 is twisted, as at 19, and its upper end is posi-

tioned in a vertical plane and is provided with a shade-receiving socket or notch 20 constituting shade-holding means, as it is immaterial whether the holding means 20 is a notch provided with parallel walls, or whether it is an aperture for receiving the stub-shaft, which is usually secured to one end of a shade. The portions 13 and 16 are provided with registering apertures 21; the 10 aperture 21 in portion 16 being formed above the bulged portion 17. In the apertures 21 is positioned a clamping member, for instance, screw 22, which screw is threaded at its inner end into aperture 21 of portion 15 13, thereby clamping the bulged portion 17 upon the body 1 of the clamp and securing the vertical bracket in an adjusted position. By reason of this fastening means, for securing portions 13 and 16 together, it will be 20 noted that I have provided a single-piece bracket for supporting a curtain-pole and a shade, which is provided with parallel portions, having clamping or gripping means for holding said bracket in an adjusted position upon a clamp, whereby the single device can be used upon a window, or upon widows, for supporting shades or curtain-poles of different lengths.

When it is desired to adjust the bracket 30 upon the body of the clamp, all that is necessary is to loosen screw 22 and slide said bracket longitudinally of the straight, flat body 1 to the desired position. I have only described one device, but it will be obvious 35 that two devices will be necessary upon a frame for supporting the ends of a shade or curtain-pole, or both. The device is artistic in appearance, and the bracket is exceedingly simple in structure, as well as efficient 40 in operation. Owing to the resiliency of the bracket, the same may be assembled with the body 1 of the clamp by inserting the apertured extension 4 into the bulged portion 17 before bending said end 4 to its right-angled 45 position, or by spreading the portions 13 and 16 apart, the body 1 can be placed between said portions and in the bulged portions 17 by merely removing the clamp from off of the support; subsequently, the portions 17 and 13 can be held together and the 50 sliding bracket secured in an adjusted position upon the body 1 by means of the fastening member or screw 22.

What I claim is:

55 1. In a device of the character described, the combination with a clamp provided with a body portion, of a bracket slidably mounted upon said body portion, said bracket formed from a single-piece of 60 resilient material and comprising a vertical portion provided at its upper end with an angularly-disposed portion, said angularly-disposed portion provided with a curtain-

pole receiving socket, said vertical portion provided at its lower end with an integral 65 portion bent back thereon, and producing a parallel portion provided with a bulged portion intermediate its ends, the body of the clamp positioned in said bulged portion, means fastening said vertical portion and the parallel portion together for causing the bulged portion to clamp said body portion and secure the bracket in an adjusted position upon the body of the clamp, said parallel portion provided at its upper end with 70 an angularly-disposed portion, and said angularly-disposed portion twisted at its outer end and the twisted portion terminating in vertical shade-receiving or supporting means. 80

2. In a device of the character described, the combination with a clamp provided with a body portion, of a bracket slidably mounted upon said body portion, said bracket formed from a single-piece and provided with a pair of parallel portions integrally connected at one end, said body portion of the clamp positioned between said parallel portions, means clamping said parallel portions upon said body portion, 90 and each parallel portion provided at its upper end with curtain-supporting means. 85

3. In a device of the character described, the combination with a support, of a bracket slidably mounted upon said support, said bracket formed from a single-piece and provided with an outer and an inner portion, the outer portion provided with an angularly-disposed extension, said extension provided with shade-supporting means, said 95 inner portion provided with an angularly-disposed portion, said last-mentioned angularly-disposed portion overhanging the extension and provided with pole-receiving means positioned beyond the shade-supporting means and the first-mentioned angularly-disposed portion. 100

4. In a device of the character described, the combination of a clamp, provided with a body terminating at its ends in angularly-disposed extensions, one extension provided with a penetrating portion, the other extension provided with an aperture, a thumb-bolt or screw threaded into said aperture, a 110 slidable jaw carried by said body and engaged by said thumb-bolt or screw, said sliding jaw comprising an angle-body provided near one end with a penetrating point, said last named body provided with a pair of parallel apertured lugs, the first-mentioned body positioned in the apertures of said lugs, and a bracket slidably mounted upon the first-mentioned body. 115

5. In a device of the character described, the combination of a clamp comprising a 125 body provided at one end with a fixed jaw

and at its opposite end with a right-angled apertured-extension, an adjusting member threaded into said extension, a slidable jaw normally engaging the inner end of said 5 adjusting member, said jaw comprising an angled-body provided with a pair of apertured lugs surrounding the body of the clamp, and a bracket slidably mounted upon

the body of the clamp between the fixed and sliding jaws.

10

In testimony whereof I hereunto affix my signature in presence of two witnesses.

THOMAS S. PLIKERD.
